UNITED STATES PATENT OFFICE.

EUGENE BIERACH, OF MILWAUKEE, WISCONSIN.

ANCHOR FOR FLASHINGS.

1,318,347.

Specification of Letters Patent. Patented Oct. 14, 1919.

Application filed March 29, 1918. Serial No. 225,547.

To all whom it may concern:

Be it known that I, EUGENE BIERACH, a citizen of the United States, residing at Milwaukee, county of Milwaukee, and State 5 of Wisconsin, have invented new and useful Improvements in Anchors for Flashings, of which the following is a specification.

My invention relates to improvements in anchors for flashings.

10 The object of my invention is to provide a more effective anchor than those heretofore used without increasing the cost of manufacture; also to provide an anchor which may be stamped from sheet metal and 15 thus produced rapidly in any desired quantity at minimum cost; also to provide a form of anchor which may be readily driven into position without destruction of the retaining lip to be subsequently bent into engagement with the flashing.

20 In the drawings:—

Figure 1 is a plan view of an anchor for flashings embodying my invention.

Fig. 2 is a side view.

25 Fig. 3 is a sectional view drawn on line 3—3 of Fig. 2.

Fig. 4 is a sectional view of a fragment of a building wall and its roof drawn to a plane exposing one of my improved anchors 30 in position for use.

Like parts are identified by the same reference characters throughout the several views.

My improved anchor comprises a compound wedge having side margins tapered toward its inner end, and raised flanges or margins also tapering toward its inner end and in the direction of the base or body portion of the anchor. It is formed from a flat 35 piece of sheet metal cut to the contour indicated by dotted lines in Fig. 1 and then struck up to form a channel-shaped member having a base 1 and raised flanges 2 with a flat tongue 3 at one end provided with 40 forwardly tapering margins and a projecting lip 4 at the other end preferably having rounded margins as shown.

The flanges 2 converge in the direction of the tongue 3 along lines co-incident with 45 the side margins of the tongue 3 and the upper margin of which flange 2 extends downwardly in the direction of the base 1 to the junction of these flanges with the tongue 3, whereby the base 1 and tongue 3 comprise 50 a wedge shaped member having wedge shaped marginal flanges terminating in

points at the front end of the base 1, i. e., at its junction with the tongue 3.

The material of which my improved anchor is composed is sufficiently flexible to 60 allow the lip 4 to be bent at right angles to the base 1 after the anchor has been driven into position for use. The rear ends of the flanges 2 afford a means whereby the anchor may be driven into position without distort- 65 ing the lip 4.

In use, a recess 6 may be formed between bricks in a portion of the wall projecting above the roof of the building and the sheet metal flashing 7 may have its outer margin 70 8 bent at right angles to the vertical portion and inserted in this recess, after which the anchor may also be inserted in the recess above the portion 8 of the flashing and driven into position as shown in Fig. 4. 75 The anchor is preferably made of sufficient length to extend beyond the inserted portion 8 of the flashing and it may be driven into the mortar or other material composing this portion of the wall of the building be- 80 yond the recesses previously formed if the material will permit. When the anchor is being driven into place, the wedge-shaped flanges 2 will cut into the material above the recess, and owing to their inclined up- 85 per margins, the anchor will be pressed downwardly with great force upon the inserted portion 8 of the flashing. After the anchor has been driven into the wall until all portions thereof are embedded except the 90 lip 4, the latter may be bent downwardly against the vertical portion 7 of the flashing as also shown in Fig. 4, whereby the flash- 95 ing is held in position not only by the downward pressure of the anchor base 1 upon the portion 8, but also by the down- 100 turned lip 4 upon the outer surface of the vertical portion 7. As above stated, the ends of the flanges 2 adjacent to the lip 4 may be utilized as shoulders to facilitate driving the 100 wedge into position. This is also true of the rounded shoulders on the base at the respective sides of the lip 4. All of the shoulders are in the planes along which the driving pressure is exerted, and therefore the anchor 105 can be readily driven into position without distorting the lip. This is of considerable importance, for the reason that an undis- 110 torte lip can be readily bent into a position to securely hold the flashing.

I claim.

1. An anchor for flashings, comprising a

flat base tapered toward one end and provided with side flanges each tapering to a point adjacent to said end of the base, the opposite end being provided with a shoulder adapted to facilitate driving it into position and the base being extended beyond said shoulder to constitute a lip, said anchor being composed of sheet metal cut and struck up at the sides to form said wedge-shaped side flanges, and the material being sufficiently flexible to permit the lip to be bent downwardly upon the vertical portion of the flashing after the other portions of the anchor have been driven into a wall above the flashing, substantially as described.

2. The combination with the wall of a building provided with a sheet metal flashing having one margin inserted in a recess of said wall, of an anchor for the flashing embedded in said wall above the inserted portion of the flashing and constituting a compound wedge having a base portion in pressure relation to the flashing and raised flanges provided with upper margins in pressure relation to the material composing the wall, said base being also provided with

a lip projecting downwardly and engaging the outer surface of the exposed portion of the flashing, substantially as described.

3. An anchor wedge for flashings, comprising a piece of sheet metal struck up to provide a flat base tapered toward one end, and shouldered at the other end, with an intermediate lip adapted to be bent downwardly between the shoulders, said base having upwardly extending side flanges, each tapering toward the base adjacent to the narrow end thereof, and said shoulders, together with the raised ends of the side flanges, being adapted to receive driving impacts in the planes of the base and side flanges respectively, whereby the anchor may be driven into position without disturbing said lip, and the lip subsequently bent down to engage the upturned portion of a flange.

In testimony whereof I affix my signature in the presence of two witnesses.

EUGENE BIERSACH.
